UNITED STATES PATENT OFFICE.

JOHN G. JONES, OF ROCHESTER, NEW YORK, ASSIGNOR TO EASTMAN KODAK COMPANY,
OF ROCHESTER, NEW YORK, A CORPORATION OF NEW YORK.

COATING APPARATUS.

1,317,138.

Specification of Letters Patent. Patented Sept. 23, 1919.

Application filed April 15, 1918. Serial No. 228,702.

To all whom it may concern:

Be it known that I, JOHN G. JONES, a citizen of the United States of America, residing at Rochester, in the county of Monroe 5 and State of New York, have invented certain new and useful Improvements in Coating Apparatus, of which the following is a full, clear, and exact specification.

This invention relates to apparatus for 10 the manipulation of vapor-evolving compositions such as plastic or coating compounds containing volatile solvents. Since my invention finds an important application in the coating arts, like varnishing, 15 lacquering, painting, etc., I shall describe such an application of it by way of illustration, but it will be understood that my invention is not limited to this particular example except as indicated in the claims. 20 One object of my invention is to provide an apparatus in which the evolved vapor will be recovered or condensed under efficient conditions but without preventing proper and easy manipulation of the vapor- 25 evolving composition. Another object of the invention is to provide an apparatus in which the composition may be readily seen and manipulated by an operator without the latter being brought into injurious 30 contact with the vapor. A still further object of my invention is to provide a coating chamber in a wall of which there is located a substantially gas-tight but shiftable device which permits convenient manual access 35 to the interior thereof, even throughout an extended zone, without the admission of undesirable amounts of air. Yet another object is to provide an apparatus in which the work operated upon will be adjust- 40 ably supported to bring successive portions thereof into the operating or coating zone, such adjustments being effected or controlled from the exterior of the apparatus. A further object is to provide easily and 45 safely controlled power drives for the parts of the apparatus. Other objects will hereinafter appear.

In the accompanying drawing in which like reference characters indicate correspond- 50 ing parts throughout the several views,—

Figure 1 is a side elevation of the coating or manipulating chamber and its associated mechanism;

Fig. 2 is a plan view of the same;

Fig. 3 is a detail end elevation showing 55 part of the gearing associated with the chamber;

Fig. 4 is a detail sectional view on the line 4—4 of Fig. 1, parts being broken away;

Fig. 5 is an end elevation of the coating 60 or manipulating chamber with its associated mechanism;

Fig. 6 is a transverse sectional view of the chamber taken on the line 6—6 of Fig. 2;

Fig. 7 is a side elevation of a frame in 65 which is fastened work to be operated upon, parts being broken away;

Fig. 8 is a detail sectional view on the line 8—8 of Fig. 1;

Fig. 9 is a diagrammatic view illustrating 70 the embodiment of my invention in which the manipulating chamber is connected with a condenser;

Fig. 10 is a detail sectional view taken on line 10—10 of Fig. 11;

Fig. 11 is a detail sectional view on line 11—11 of Fig. 10;

Fig. 12 is a detail perspective of a spring part.

In varnishing, lacquering, painting and 80 similar operations where volatile solvents are given off during drying, their vapor is frequently allowed to escape and become wasted. The coating is generally performed by hand in an open room or in a chamber 85 which is open on one side to give the workmen manual access to the interior. If it be attempted to withdraw the vapor from such room or chamber and treat it for recovery of the solvents, a large amount of air 90 will dilute it and thus make the recovery inefficient and uneconomical. My problem has, therefore, been to combine with a condenser a coating chamber, which will be substantially gas-tight and yet will permit 95 a workman, located outside the chamber, to have manual access to the coating zone in the chamber. The practically undiluted vapor from such a tight chamber is, of course, easily condensed. The problem has 100 been particularly difficult to solve where the objects to be coated are of such shapes or sizes that the coating must be performed throughout an extended area or zone. My present solution of the problem is adapted 105 to meet this difficulty and I have, therefore,

chosen as the illustrative embodiment of my invention an apparatus in which long narrow aeroplane wings are coated.

In some instances the evolved vapors may 5 be poisonous and it is highly important to withdraw them so as to protect the workman. My coating chamber is useful in such cases irrespective of whether the solvents be recovered or not.

- 10 In the drawing 1 denotes the coating chamber generally. Its shape, being made to correspond to the object to be coated, is shown as long and narrow, to accommodate the aeroplane wings 2 mounted in frames 3, 15 using any suitable or preferred attaching devices, such as perforated ears 4 and pintles 5 and adjustable pins 6 fitting in sockets 7. The end of the casing, as best shown in Fig. 5, is provided with a hinged door 8 which 20 is provided with any preferred lock and gaskets (not shown), so as to render it substantially gas-tight when properly closed.

Within the casing and in line with the door is a vertical support 9, the driving 25 means of which will be hereinafter described. In use, the frame 3 with its contained object 2 is located upon support 9 which carries it vertically upward across the spaces or zones where the varnishing is 30 performed.

The mechanism adjacent these zones constitutes an important feature of my invention. The side walls 10 of the casing 1 are provided intermediate their height with 35 laterally extending enlargements or side chambers 11. Each side chamber is composed of a framework bearing an upper inclined transparent window 12 of pyroxylin, glass or any equivalent transparent material 40 which remains uninjured when in contact with the evolved vapor. The lower face of each member is defined by a gas-tight inclined wall 13. The vertical intermediate face of each side chamber is provided with 45 an elongated horizontal slot or opening 14, constantly covered in a substantially gas-tight manner by a flexible belt 17, composed of any suitable impervious material, such as heavy leather treated if necessary to make it 50 resistant to the vapor. Each belt passes over and is windable back and forth upon two rollers 15, supported in suitable bearings 16 upon the frame of the chamber 1. The driving means for the belt and rolls 55 will be hereinafter described. It is important that the edges of the belt be constantly kept in substantially gas-tight engagement with the edges of the elongated opening 14, and I have found the following arrangement 60 satisfactory for this purpose.

Referring to Fig. 4, the belt 17 rests at its horizontal edges against rounded ridges 18 on the frame work 140 surrounding the opening 14. The edges of the belt are kept in constant engagement with such ridges by

means of flexible plates 19 which are pushed by springs 20 against the belt, such springs being located in pockets in the bars 22 which are fastened to the framework 140 by screws 23 which also attach plates 19. 70 Before passing to the rolls 15 the belt 17 passes over and makes slight frictional contact with guides 24 (see Fig. 2).

The belt 17 is kept in substantially gas-tight engagement with the vertical edges of 75 opening 14 by means of the devices shown in Figs. 10, 11 and 12. The belt 17 is pressed against the frame 141 by the individually yielding sections 91 of the slotted channel plates 90, each section being pressed 80 by a spring 92 located in a pocket 93 in a cross bar 94. Bars 94 are attached to frame 141 by screws 95. The sides of plates 90 embrace the sides of bars 94 to hold said plates in position as shown in Fig. 11, and 85 to permit them to move bodily toward the belt, such motion together with the individual movements of sections 91, compensating for any unevenness in the belt.

Each belt is provided with an arm hole 25 90 surrounded by a flexible impervious or vapor-resisting sleeve 26 through which the arm of the operator may be thrust, as indicated in Fig. 6. This sleeve is of general frusto-conical shape, the larger end of it being 95 attached around the edges of the arm hole 25 by sewing, cementing or any other preferred way. In the drawing I have illustrated it as being riveted between the belt and the circumferential metallic band 27. 100 The smaller end of the sleeve may be provided with an elastic band to close it when the operator's arm is withdrawn and to make gas-tight engagement with his arm when it is inserted. At either side of the 105 sleeve 26 there is located a vertical stiffening strip 32 which prevents the belt from buckling.

The coating chamber, so far described, is sufficient by itself, to protect the workman 110 from injurious contact with the vapor, which may be allowed to escape or be withdrawn through the pipes 31 at the bottom of the casing, each pipe having a valve 310. It is generally preferable, however, to connect the chamber and its exit pipes 31 with an apparatus for condensing the withdrawn vapor. Thus in Fig. 9 I have diagrammatically indicated the exit pipes 31, as connected with a condenser 29, the internal 115 structure of which is not shown because it may be of any of the forms well known to persons skilled in this art. For instance, the condenser 29 may be an absorption or scrubbing tower in which the vapor is removed 120 from the gas or air by being brought into intimate contact with a solvent of such vapor; sulfuric acid being often used to take up alcohol or ether, bisulfite liquor being sometimes employed to combine with 125 130

acetone, and high boiling low-volatile hydrocarbons or organic bodies being used to dissolve vapors of benzene and volatile hydrocarbons and their substitution products. But any of the known equivalent condensers may be substituted, of course.

The gas or air from which the vapor has been largely removed by condenser 29, is discharged by fan 33 through pipe 28 into the external atmosphere or a stack may be used to produce a mild draft. A slight vacuum may thus be maintained in the system if desired.

It is obvious that the chamber can usefully operate with only one coating zone and shiftable belt. The operator would first coat one side of the object and then after reversing the latter would coat the remaining side. Generally, however, and particularly in the case of aeroplane wings, it is desirable for two persons to work simultaneously upon opposite sides, and, therefore, in my preferred chamber I provide opposite coating zones, as indicated in Fig. 6, thus making the casing substantially symmetrical in cross section.

It will be also apparent that the belt 17 could be shifted by the operator pulling thereon, or by rotating some hand operated means connected with the rolls 15. Furthermore, the support 9 could be manually adjusted vertically. In practice, however, I have found it preferable to provide for driving the parts of my apparatus from a source of power, such as a power shaft or an electric motor. The mechanism by which I accomplish this result in the preferred form of my invention will now be described.

A source of power, such as motor 35, is connected by pulleys 36, 37 and belt 38 with one of the longitudinal main shafts 46, the latter being mounted upon bearings 59 at the base of the machine. These shafts carry sprocket wheels 47 connected by chain 48 so as to turn in unison. Each shaft 46 has clutch sleeves 49 keyed to move longitudinally thereon and rotate therewith, such sleeves facing in opposite directions and being actuated by yokes 50 carried by stub shafts 51 which are turned by arms 52 carried thereon, these arms being connected by a cross rod 53. The cross rods are located adjacent the belts 17, so as to be conveniently accessible to the operator. The cross rod 53 in addition to being a convenient actuating means for the clutch sleeves 49 also serves through arms 52 to keep such sleeves in such spaced relation that they may engage either of their coöperating clutch collars 55 or may both be located in an intermediate inactive position. The clutch collars 55 together with the worms 56 carried thereby are freely rotatable on shafts 46 and operate shafts 58 through gears 57.

Shafts 58 rotate the flanged rolls 15. From this description it will be seen that an operator upon either side of the machine can, by moving the adjacent rod 53, throw in the proper clutch and move the corresponding belt either in one direction or the other, the worms 56 on each side of the machine being one right handed and the other left handed as shown in Fig. 1. The belt being pulled across opening 14, the friction of the parts is sufficient to maintain the belt free from slack.

If some means were not provided to stop the belt automatically, undue stresses might be imposed upon the parts when the belt carries the sleeve 26 to the end of the opening 14. To guard against such contingency, I mount the levers 60 near the ends of the opening 14 on pivots 61 so that their lower ends may contact with the upper ends of arms 52. The upper ends of levers 60 are curved inwardly into the path of movement of stiffening strips 32, the parts being so proportioned that whenever the forward strip 32 contacts with its lever 60 the lower end thereof will shift arms 52 and bring the clutches into inactive position, thereby stopping movement of the belt.

On the end of each shaft 46 is a beveled gear 45 which drives a coöperating beveled gear 44 rotatable on cross shaft 34, the gears 44 being faced in opposite directions, so as to rotate in opposite ways. Rotating with each gear 44 is a clutch collar 43 adapted to coöperate with one of the clutch sleeves 40 keyed to rotate with, but slide longitudinally of, shaft 34. These sleeves 40 have the usual grooves 41 in which fit the ends of the spacing and operating yoke 42. The latter holds the sleeves so spaced that only one of them can mesh with its coöperating collar at a time, and the dimensions are such that in the intermediate position neither clutch operates. Rotating with shaft 34 is a collar 62 carrying a helical spring 63 which bears against a friction disk 64 keyed on shaft 34 and pushes the disk against a coöperating friction disk 65 which turns the worm 66. Since the latter is rotatable on shaft 34, it is frictionally driven through the disks 64 and 65, thus allowing the parts to slip in case of stresses that are above normal. Gear 67 carried on longitudinal shaft 68 beneath the main floor 69 of the machine is rotated by worm 66. Shaft 68 turns pinions 70 meshing with racks 71 connected to support 9, the ends of the latter moving in vertical guides 77.

Racks 71 enter the chamber through substantially gas-tight packing devices shown in Fig. 8. The racks pass through openings in floor 69 which is provided with packing segments 82 bearing against the rear and sides of the racks and is also provided with spring pressed packing plates 83 carried on

rods 84 slidable in horizontal bores in the floor, said plates 83 being pressed against the teeth of the rack by springs 85.

The yoke 42 is guided by link 72 pivoted centrally thereon and on the frame. This link carries a pin 74 which engages and is driven by cam 73. The cam 73 is carried by shaft 78 turning in bearings 75, said shaft being actuated by means of hand levers 76. 10 When the levers 76 are moved, thereby correspondingly moving the cam 73, the link 72 and yoke 42 are shifted to bring one of the clutch sleeves 40 into engagement with its collar 43, thereby rotating the shaft 34 forward or backward, as the case may be, and consequently through the friction disks 64, 65 and gears 66, 67 rotating the shaft 68 to move the support 9 up or down through racks 71 and pinions 70. I find it convenient to connect levers 76 with auxiliary levers 79, pivoted at 80 at the opposite end of the apparatus, by means of rods 81, which, like rods 53, are located adjacent the belts 17 where they can be conveniently reached by the hand of the workman. 25

In the chamber I may use electric lights 82 inclosed in protecting globes 83 to avoid fire risk if the vapors be inflammable.

The operation of the apparatus is as follows: The support 9 being at its lowest station, the several clutches being in the neutral or inactive position, and the valve 310 being closed the workman opens door 8 and slides a frame 3, containing a wing 2, onto support 9. Door 8 is then closed. This opening and closing of the door does not in practice interfere with efficient solvent recovery if the gas-tight condition of the chamber be restored before the coating begins. Valve 310 is opened. The workman, one on each side of the chamber, then inserts an arm through the sleeve 26 and applies the coating to the upper horizontal strip of the wing, shifting the belt 17 sideways, either step by step or continuously, by suitably manipulating rod 53 which controls the belt winding mechanism. The workman next shifts rod 81 to vertically move the support 9 and bring a fresh horizontal strip of the wing into the coating zone. This strip is then coated, the belt being shifted horizontally as before. By repeating these operations the whole wing surface is brought into the coating zone, a strip at a time, and completely coated, and recoated if desired. 55

While I prefer to operate as above described, by alternating short vertical movements of support 9 with full movements of belt 17 back and forth, thereby coating horizontal strips, it is possible to coat in vertical strips by alternating full movements of support 9 with short horizontal shifts of the belt. If at any time it is desirable to treat any particular portion of the wing,

the workman has only to shift the support 9 and belt 17 to bring such portion where he can reach it. It may be noted that the belt acts, to a certain extent as a horizontal guide for the workman's arm. 70

The coating may be applied in any suitable way such as by an ordinary brush, or an air brush, or by a fountain brush, one of the latter being indicated at 86 in Fig. 6. The hose 87 supplying the coating liquid 75 to the brush may be introduced through sleeve 26 with the operator's arm or may pass through a hole in the belt as shown in Fig. 6.

In practice when coating wings I find that 80 the current of gas or air in the chamber is sufficiently evenly distributed to require no special gas directing means. In case irregularly shaped articles are coated, gas distributing baffles may be readily placed 85 in the chamber to coöperate with pipe 28.

I have shown the belt 17, drawn along a straight path between straight guides but it is clear that such a flexible shifting means can be pulled along curved or irregularly 90 shaped chamber walls through correspondingly shaped guides, and still act as a substantially gas-tight closure. By substantially gas-tight I mean that the entrance of diluting air is prevented sufficiently to insure efficient recovery of the solvents from the vapor. 95

Instead of ordinary coating it is obvious that any other manipulation of vapor evolving compounds may be performed in my 100 apparatus, the operator being outside the same, such as operating molds for plastic compounds, like pyroxylin. Therefore I use coating in a generic sense in the following claims. 105

By deflecting the ends of the slide or belt 17 about rolls 15, the apparatus requires much less room, than it would if the ends projected straight out.

Having thus described my invention, what 110 I claim and desire to secure by Letters Patent of the United States, is:

1. An apparatus for coating with vapor-evolving compositions, comprising a coating chamber, and a substantially gas-tight device 115 shiftable along a wall of said chamber while permitting manual access through said device to the interior thereof.

2. An apparatus for coating with vapor-evolving compositions, comprising a coating 120 chamber, a substantially gas-tight device shiftable along a wall of said chamber while permitting manual access through said device to the interior thereof and means for shifting said device.

3. An apparatus for coating with vapor-evolving compositions, comprising a coating chamber having an opening in a wall thereof, a slide movable across said opening but throughout its movement substantially 130

- closing said opening, and a substantially gas-tight device on said slide permitting manual access through said device to the interior of said chamber from the exterior 5 thereof.
4. An apparatus for coating with vapor evolving compositions, comprising a coating chamber having an opening in a wall thereof, a slide movable across and closing 10 said opening, a substantially gas-tight device on said slide permitting the operator to manually control the coating in said chamber through said device from the exterior thereof, and manually controlled 15 power driven means for moving said slide.
5. An apparatus for coating with vapor evolving compositions, comprising a coating chamber having an opening in a wall thereof, a flexible slide movable across said 20 opening in substantially gas-tight connection with the edges of said opening, a substantially gas-tight device on said slide permitting manual access through said device to the interior of said chamber and means 25 for moving said slide.
6. An apparatus for coating with vapor evolving compositions comprising a coating chamber having an opening in a wall thereof, a flexible belt having an arm hole 30 therein and movable across said opening, yielding devices for pressing the belt into substantially gas-tight contact with the edges of said opening, and a flexible sleeve surrounding said arm hole.
7. An apparatus for coating with vapor evolving compositions, comprising a coating chamber, a substantially gas-tight device permitting the operator to manually control 35 through said device the coating of an object from the exterior of the chamber, and a support for the object movable in the chamber relative to said device.
8. An apparatus for coating with vapor evolving compositions, comprising a coating chamber, a substantially gas-tight device 40 shiftable along a wall of said chamber while permitting manual access through said device to the interior thereof, and a support movable in said chamber relative to said device.
9. An apparatus for coating with vapor evolving compositions, comprising a coating chamber, a substantially gas-tight device shiftable along a wall of said chamber while 45 permitting manual access through said device to the interior thereof, means for shifting said device, a support movable in said chamber relative to said device, and means for moving said support.
10. An apparatus for coating with vapor evolving compositions, comprising a coating chamber having an opening in a wall thereof, a slide movable across and closing 50 said opening, a substantially gas-tight device on said slide permitting the operator to 55
- manually control through said device the coating in said chamber from the exterior thereof, manually controlled means for moving said slide, a support movable in said chamber relative to said slide, and manually 60 controlled means for moving said support.
11. An apparatus for coating with vapor evolving compositions, comprising a coating chamber, a substantially gas-tight device shiftable along a wall of said chamber while 65 permitting manual access through said device to the interior thereof, and a gas-tight transparent window in said wall adjacent said device.
12. An apparatus for coating with vapor- 70 evolving compositions, comprising a coating chamber having an opening in a wall thereof, a slide movable across said opening but throughout its movement substantially closing said opening, a substantially gas- 75 tight device on said slide permitting manual access through said device to the interior of said chamber from the exterior thereof, and a gas-tight transparent window in the wall of said chamber above said slide.
13. An apparatus for coating with vapor- 80 evolving compositions, comprising a coating chamber, a substantially gas-tight device permitting the operator to manually control through said device the coating of an object 85 from the exterior of the chamber, a support for the object movable in the chamber relative to said device, and a window in the chamber adjacent said device.
14. An apparatus for coating with vapor- 90 evolving compositions, comprising a coating chamber, a substantially gas-tight device shiftable along a wall of said chamber while permitting manual access through said device to the interior thereof, means for shifting 95 said device, a support movable in said chamber relative to said device, means for moving said support, a transparent window in said chamber, and means for illuminating the interior of the casing.
15. An apparatus for coating with vapor- 100 evolving compositions, comprising a coating chamber having an opening in a wall thereof, and means for substantially closing said opening during the coating operation, said 105 means including a device shiftable along said wall across said opening and permitting the operator to manually control the coating in said chamber through said device from the exterior thereof.
16. An apparatus for coating with vapor- 110 evolving compositions, comprising a coating chamber having an opening in a wall thereof, rolls at opposite sides of said opening, a belt connected to said rolls and movable 115 across but substantially closing said opening, a substantially gas-tight device on said belt permitting manual access through said device to the interior of said chamber, a source of power, and manually controlled 120
17. An apparatus for coating with vapor- 125 evolving compositions, comprising a coating chamber having an opening in a wall thereof, a slide movable across and closing said opening, a substantially gas-tight device on said slide permitting the operator to 130

- connections between said source of power and said rolls.
17. An apparatus for coating with vapor-evolving compositions, comprising a coating chamber, a substantially gas-tight device shiftable along a wall of said chamber while permitting manual access through said device to the interior thereof, a window in a wall of said chamber adjacent said device, and means for illuminating the interior of the chamber. 50
18. An apparatus for coating with vapor-evolving compositions, comprising a coating chamber having an opening in the wall thereof, a slide movable across said opening but throughout its movement closing said opening, a substantially gas-tight device on said slide and movable therewith from one side of said opening to the other and permitting manual access through said device to the interior of said chamber from the exterior thereof, means for moving said slide, and means for automatically stopping the movement of the slide when the device nears a side of said opening. 55
19. An apparatus for coating with vapor-evolving compositions, comprising a coating chamber, a substantially gas-tight device movable between limits along a wall of said chamber while permitting manual access through said device to the interior thereof, and means for automatically stopping movement of said device upon reaching said limits. 60
20. An apparatus for coating with vapor-evolving compositions, comprising a coating chamber, a substantially gas-tight device movable along a wall of said chamber while permitting manual access through said device to the interior thereof, means for moving said device, and a member on the device controlling said means. 65
21. An apparatus for coating with vapor-evolving compositions, comprising a coating chamber, and substantially gas-tight devices 70
- in the opposite walls thereof shiftable independently along said walls while permitting manual access through said device therethrough to the opposite sides of an object contained in said chamber. 75
22. An apparatus for coating with vapor-evolving compositions, comprising a coating chamber, a substantially gas-tight device shiftable in a defined path along a wall of said chamber while permitting manual access through said device to the interior thereof, and a support in said chamber adjustable in a direction at an angle to said path of the device. 80
23. An apparatus for coating with vapor-evolving compositions, comprising a coating chamber, a substantially gas-tight device shiftable horizontally along a wall of said chamber while permitting manual access through said device to the interior thereof, and a vertically adjustable support in said chamber. 85
24. An apparatus for coating with vapor-evolving compositions, comprising a chamber having an opening in a wall thereof, a flexible device movable across said opening but throughout its movement substantially closing said opening while permitting manual access through said device to the interior of said chamber, and means for deflecting the ends of the device. 90
25. An apparatus for coating with vapor-evolving compositions, comprising a chamber having an opening in a wall thereof, a flexible device longer than said wall, shiftable across and substantially closing said opening while permitting manual access through said device to the interior of said chamber, and means at the ends of said wall for deflecting the ends of said device into a substantially non-projection position. 95

Signed at Rochester, New York, this 5th day of April 1918.

JOHN G. JONES.
